UNITED STATES PATENT OFFICE.

ROBERT LYONS, OF NEW YORK, N. Y.

AUTOMOBILE SIGNAL.

Application filed October 10, 1922. Serial No. 593,624.

To all whom it may concern:

Be it known that I, ROBERT LYONS, a citizen of the United States, and a resident of Rosebank, in the borough of Richmond, city of New York, and State of New York, have invented a new and Improved Automobile Signal, of which the following is a full, clear, and exact description.

This invention relates to improvements 10 in automobile signals, and more particularly to direction signals to indicate the direction of turning of the vehicle, an object of the invention being to provide a signal of improved construction in which the signal 15 plates and colored glass can be conveniently removed and replaced, and furthermore provide a construction which permits ready access to the lamp as occasion may require.

A further object is to provide a signal of 20 the character stated which can be manufactured and sold at a reasonably low price, which will be strong and durable, which will be ornamental in appearance, and which will most efficiently perform the functions for 25 which it is intended.

With these and other objects in view, the invention consists in certain novel features of construction and combinations, and arrangement of parts, as will be more fully 30 hereinafter described and pointed out in the claim.

In the accompanying drawings—

Figure 1 is a view in front elevation of 35 my improved signal.

Figure 2 is a view in horizontal transverse section on the line 2—2, of Figure 1.

Figure 3 is a view in end elevation of the righthand end of Figure 1.

Figure 4 is a view in vertical transverse 40 section on the line 4—4, of Figure 1.

1 represents the casing of my improved signal. This casing is of elongated oblong shape having curved ends. Throughout its longitudinal edges and on one curved end 45 it is provided with integral, inwardly projecting flanges 2.

Angle bars 3 are secured to the inner 50 faces of the top and bottom of the casing, are longitudinally positioned, and are spaced from the flanges 2 the proper distance so that in co-operation with said flanges the bars 3 constitute guides for the reception of plates 5 and colored glass 6.

The curved end 7 of casing 1 is cut away or made appreciably narrower than the main portion of the casing so as to provide entrances and exits for the plates 5 and glass 6 allowing both plates and glass to be slid longitudinally into or out of the casing, and when in the casing securely held by the flanges 2 and the bars 3.

The plates 5 are cut out to form arrows 8 or other figures indicating direction and the glass plates 6 are preferably red so that the illumination from a lamp 4 secured within the casing will show a red arrow indicating direction.

To hold the plates 5 and glass plate 6 against movement, curved covers 9 are provided at the entrance end of the casing. 70 These covers 9 conform to the shape of the casing and have flanges 10 which register with the flanges 2 and complete the enclosure of plates 5 and 6.

The covers 9 are also provided with perforated tongues 11 extending over the end 7 of casing 1 and secured by screws or bolts 12 which are projected through the perforated ears, through perforations in the end 7, and screwed into a bar 13 against the inner face of the end 7. This bar 13 may constitute a fixed part of the end 7 if desired to reinforce the same and to provide sufficient bearing surface for the screw threads of the screws or bolts 12.

In operation it is simply necessary to remove the covers 9 when the plates 5 and 6 can be slid longitudinally into or out of the casing to allow for repairs or for cleaning the glass.

Various slight changes might be made in the general form and arrangement of parts described without departing from my invention, and hence I do not limit myself to the precise details set forth, but consider myself at liberty to make such changes and alterations as fairly fall within the spirit and scope of the appended claim.

I claim:

A device of the character stated, comprising an oblong casing having openings at its edges at one end, inwardly projecting flanges throughout both longitudinal edges and one curved end of said casing, bars secured to the upper and lower faces of the casing and co-operating with the flanges to

form guides, plates and sheets of colored glass supported in said guides and movable through the openings in the ends of the casing, said plates having direction indicating openings therein, covers for the openings in the ends of the casing, flanges on said covers registering with the flanges of the casing, perforated tongues on the covers projecting over the end of the casing, a bar located against the inner face of the end of the casing, and securing devices through the tongues and the end of the casing and secured in the bar.

ROBERT LYONS.
